UNITED STATES PATENT OFFICE.

WALTER J. RICHARDS, OF MILWAUKEE, WISCONSIN.

CONTROLLING APPARATUS.

No. 821,747.

Specification of Letters Patent.

Patented May 29, 1903.

Application filed July 2, 1903. Serial No. 164,086.

To all whom it may concern:

Be it known that I, WALTER J. RICHARDS, a citizen of the United States, residing at Milwaukee, in the county of Milwaukee and State of Wisconsin, have invented a certain new and useful Improvement in Controlling Apparatus, of which the following is a full, clear, concise, and exact description, reference being had to the accompanying drawings, forming a part of this specification.

My invention relates to means for regulating the operation of fluid-pumps, such as air-compressors, and is particularly well adapted for use in conjunction with such pumps when operated by means of an electric motor and where the fluid-pump is used for maintaining a substantially uniform or constant pressure in a pressure system.

My invention is peculiarly useful in conjunction with pneumatic-pressure systems supplied by an air-compressor driven by an electric motor, the operation of the electric motor being controlled by the pressure in the pneumatic-pressure system. In such an embodiment of my invention means are provided whereby a decrease in the pressure in the pneumatic-pressure system to a certain minimum limit causes the closure of the motor-circuit, whereby the motor is operated to drive the air-compressor, whereby the pressure in the pneumatic system is increased. Means are also provided whereby the increase in the pressure to a certain maximum limit causes a break in the motor-circuit, whereby the motor and the air-compressor connected therewith are brought to rest.

Where such a combination as I have above described is employed, it is frequently found desirable to provide an automatic rheostat for restricting the supply of current to the motor at starting. Whether or not such an automatic rheostat is employed, it is desirable that means be provided for relieving temporarily the load upon the motor at starting.

It is the principal object of my invention to provide an improved means for relieving or decreasing the load upon the electric motor at starting, whereby the motor may be brought substantially to full speed before the full load of the air-compressor is brought upon the motor. The motor may thus be brought approximately to full speed without an undue rush of current through the motor-windings, due to the heavy load of the air-compressor when discharging into the pressure system.

The features of my invention will be made apparent by reference to the accompanying drawing, diagrammatically illustrating the essential features thereof.

In the drawing I have illustrated a pipe 1, comprising a part of the pneumatic-pressure system, connected with the storage-tank 2. An air-compressor 3, comprising a cylinder 4, a piston 5, connecting-rod 6, crank 7, suction-valves 8 8, and discharge-valves 9 9, is adapted to supply the storage-tank 2 with compressed air, the pipe 10 serving to convey the compressed air from the compressor 3 to the tank 2. The air-compressor 3 has geared connection with a suitable motor means, such as an electric motor 11, comprising an armature 12, upon the commutator of which ride the brushes 13 13. The series field-winding of this motor is diagrammatically illustrated at 14. The series winding is directly connected by means of the conductor 15 with the electric main 16. Conductors 17 and 18 lead through the coils 19 and 20 and the sections 21 and 22 of a resistance-coil and through the winding 23 of a slow-acting electromagnetic switching device 24 to a contact-shoe 25, this contact-shoe being adapted when in one of its alternate positions to make electrical connection with the contact-shoe 26, which is adapted for connection with the electric main 27 by means of the main switch 28. The pipe 29 leads from the pressure-reservoir 2 to a pressure-controlled switching device 30. This switching device comprises a Bourdon tube 31, connected with the pipe 29, there being a switch-arm 32, connected, by means of the link 33, with the end of the tube 31. The switch-arm 32 is connected, by means of a conductor 34, with the shoe 25. A contact-point 35 is connected, through a conductor 36 and the solenoid 37, with the contact-shoe 26, and contact-point 38 is connected, through the conductor 39 and the solenoid 40, with the electrical main 16. A soft-iron plunger 41 is mounted to oscillate within the solenoids 37 and 40, this plunger 41 carrying, by means of an arm 42, the insulated contact-shoe 25.

When the pressure in the pressure system drops to a minimum limit, the Bourdon tube 31 becomes curved, thereby actuating the switch-arm 32 to make connection with the contact 35, whereby the following electric circuit may be traced: from the main 27, through the main switch 28, which will have been closed, contact-shoe 26, solenoid 37, conductor 36, contact-point 35, switch-arm

32, conductor 34, electromagnet-coil 23, resistances 22 and 21, solenoids 20 and 19, conductor 18, conductor 17, brush 13, armature 12, brush 13, series coil 14, and conductor 15 to the main 16. The closure of this circuit through the solenoid 37 causes an energization thereof, whereby the plunger 41 is attracted toward the left, thereby bringing the contact-shoe 25 into engagement with the contact-shoe 26, thereby short-circuiting at once the solenoid 37 to cause the deenergization thereof. The closure of the circuit through the solenoids 20 and 19 causes an energization thereof, whereby the soft-iron cores 43 and 44 are attracted upward to raise and hold the suction-valves 8 8 from their seats.

The automatic rheostat, if such be provided, is now operated to cut the resistances 22 and 21 out of the motor-circuit. This rheostat acts in the following manner: the electromagnet-coil 23, being included in the motor-circuit through contact-shoes 25 and 26, is energized, thereby causing the upward attraction of the soft-iron core 45. The rapid movement of this core is prevented by means of a dash-pot 46 or other suitable restraining means. Switch-contacts 47 are presently closed by the upward movement 30 of the core 45, thereby short-circuiting the section 22 of the resistance through the electromagnet-coil 48. The energization of this electromagnet-coil in turn causes the upward attraction of the soft-iron core 49 against the restraining influence of the dash-pot 50 to close the electrical contacts 51, whereby the section 21 of the resistance is short-circuited. The closure of the contacts 51 causes the electromagnet-coil 52 to be cut into the circuit, whereby the same is energized to cause the upward attraction of the core 53, the movement of this core being restrained by the dash-pot 54. Switch-contacts 55 are controlled by the upward movement of the core 53 to short-circuit the solenoids 19 and 20, whereby the same are deenergized to permit the closure of the suction-valves of the air-compressor 3.

The slow-acting electromagnetic device 55, which may act in conjunction with the automatic rheostat comprising electromagnetic devices 24 and 56 and the resistances 22 and 21, permits a considerable speed of the motor 11 to be attained before the suction-valves 8 8 of the air-compressor are permitted to operate. While the suction-valves 8 8 are maintained in their open condition by the energization of the solenoids 19 and 20, there is no discharge from the air-compressor 60 into the storage-tank 2, and the load upon the air-compressor is practically nothing. While the suction-valves 8 8 are maintained in their open condition, the discharge-valves 9 9 of the compressor are not operated by 65 the movement of piston 5 through the cylinder

of the compressor. Thus during the initial supply of energy, or in this case electrical current, to the motor means 11 there is practically no load upon the compressor or upon the motor, whereby the starting-current may not prove excessive to destroy the winding of the motor. After a considerable interval of time has elapsed the slow-acting electromagnetic devices are actuated to short-circuit, and thereby deenergize, the solenoids 20 and 19, 70 whereby the normal operation of the pressure-valves is permitted. The resistances 22 and 21 may, if desired, be normally included in the motor-circuit to restrict the supply of current to the motor at starting, and in the preferred embodiment of my invention, in which such an automatic rheostat is employed, the slow-acting electromagnetic device 55 is not included in the circuit until after the resistances 22 and 21 have been short-circuited and cut 75 out. The automatic rheostat, however, may be dispensed with, whereby the current at starting is not restricted by extraneous resistances. In this case the solenoids 20 and 19 may be desirably included in the circuit with the slow-acting electromagnetic device adapted after the lapse of a suitable interval of time to short-circuit or cut out these solenoids, whereby the valves of the compressor may be operated to permit a discharge from the compressor into the storage-tank 2.

After the motor has operated for a suitable length of time the pressure in the tank 2 may be brought up to a maximum limit, whereby the Bourdon tube 31 will have been sufficiently straightened to cause the switch-arm 32 to make electrical connection with the contact 38, thereby closing a circuit through the solenoid 40, whereby the same is energized to attract toward the right the soft-iron core 41. The actuation of this automatic switching device causes a break in the circuit through the electric motor, whereby the same is brought to rest.

The deenergization of the electromagnet-coils 23, 48, and 52, which are also included in the motor-circuit, permits the cores 45, 49, and 53 to drop back into their normal positions, thereby opening the associated switch-contacts and cutting the solenoids and the resistances 21 and 22 into the motor-circuit, 115 whereby the same may be again brought into service upon the closure of the motor-circuit. It will of course be apparent that the automatic controller for governing the motor-circuit may be dispensed with and a manually-operated switch substituted therefor.

Furthermore, any suitable motor means may be employed in place of the electric motor shown, and a pump adapted for use with 125 any other fluid may be substituted for the air-compressor shown.

While I have herein shown and described a preferred embodiment of my invention, it will be apparent to those skilled in the art that 130

many modifications may be employed without departing from the spirit thereof. I do not, therefore, wish to limit myself to the precise disclosure herein set forth; but,

5 Having described my invention, I claim as new and desire to secure by Letters Patent

1. In combination, an electric motor, a fluid-pump driven thereby, a pressure system supplied by said pump, switching means controlled by the pressure in said system to govern the circuit for said motor, and electrical means for preventing the operation of the suction-valves of said pump upon the closure of the circuit through said motor.

15 2. In combination, an electric motor, a fluid-pump driven thereby, switching means for controlling the circuit through said motor, and electrical means for preventing the operation of the valves of said pump upon the closure of the circuit through said motor.

20 3. In combination, an electric motor, a fluid-pump driven thereby, switching means for controlling the circuit through said motor, and automatic electrical means for preventing the operation of a suction-valve of said pump during the initial supply of current to said motor.

25 4. In combination, an electric motor, an air-compressor driven thereby, a pressure system supplied by said air-compressor, switching means governed by the pressure in said system to control the circuit through said motor, and electrical means for preventing the operation of the valves of said compressor during the initial supply of current to said motor.

30 5. In combination, an electric motor, a fluid-pump driven thereby, switching means for controlling the circuit through said motor, automatic electrical means for preventing the operation of the valves of said pump during the initial supply of current to said motor, and means for permitting the operation of said valves upon the lapse of a suitable interval after the closure of said motor-circuit.

35 6. In combination, an electric motor, a fluid-pump driven thereby, a pressure system supplied by said pump, switching means controlled by the pressure in said system to close the motor-circuit upon a decrease in the pressure in said system to a minimum and to open the motor-circuit upon an increase in the pressure in said system to a maximum limit, and electrical means for preventing the operation of the suction-valves of said pump upon the closure of the circuit through said motor.

40 7. In combination, an electric motor, a fluid-pump driven thereby, a pressure system supplied by said pump, switching means controlled by the pressure in said system to close the motor-circuit upon a decrease in the pressure in said system to a minimum limit and to open the motor-circuit upon an increase in the pressure in said system to a

maximum limit, and electrical means for preventing the operation of the valves of said pump during the initial supply of current to said motor.

45 8. In combination, an electric motor, a fluid-pump driven thereby, a pressure system supplied by said pump, switching means controlled by the pressure in said system to close the motor-circuit upon a decrease in the pressure in said system to a minimum limit 75 and to open the motor-circuit upon an increase in the pressure in said system to a maximum limit, means for preventing the operation of the valves of said pump during the initial supply of current to said motor, 80 and electrical means for permitting the operation of said valves upon the lapse of a suitable interval after the closure of said motor-circuit.

9. In combination, an electric motor, a fluid-pump driven thereby, a pressure system supplied by said pump, switching means controlled by the pressure in said system to control the motor-circuit, means for restricting the supply of current to said motor at starting, means for preventing the operation of the valves of said pump upon the closure of the motor-circuit and electrical means for permitting the operation of said valves upon the lapse of a suitable interval after the closure of said motor-circuit.

95 10. In combination, an electric motor, a fluid-pump driven thereby, a pressure system supplied by said pump, switching means controlled by the pressure in said system to control the motor-circuit, means for restricting the supply of current to said motor at starting, and electromagnetic means for preventing the operation of the valves of said pump upon the closure of the motor-circuit.

100 11. In combination, an electric motor, a fluid-pump driven thereby, a pressure system supplied by said pump, switching means controlled by the pressure in said system to control the motor-circuit, means for restricting the supply of current to said motor at starting, electromagnetic means for preventing the operation of the valves of said pump upon the closure of the motor-circuit and additional electromagnetic means for permitting 110 the operation of said valves after the removal of the restriction of the supply of current to said motor.

115 12. In combination, an electric motor, a fluid-pump driven thereby, a pressure system supplied by said pump, switching means controlled by the pressure in said system to control the circuit through said motor, means for restricting the supply of current to said motor at starting, means for preventing the closure of the suction-valves of said pump upon the initial supply of current to said motor, and electrical means for permitting the operation of said valves and for removing the restriction of the supply of current to said 125 motor.

motor after the lapse of a suitable interval after the closure of said motor-circuit.

13. In combination, an electric motor, a fluid-pump driven thereby, means for controlling the motor-circuit, means for restricting the supply of current to said motor at starting, and means for preventing the operation of the valves of said pump upon the closure of the motor-circuit and for permitting the operation of said valves after the removal of the restriction of the supply of current to said motor.

14. In combination, an electric motor, a fluid-pump driven thereby, means for controlling the motor-circuit, means for restricting the supply of current to said motor at starting, electrical means for preventing the closure of the suction-valves of said pump upon the initial supply of current to said motor, and means for permitting the operation of said valves and for removing the restriction of the supply of current to said motor after the lapse of a suitable interval after the closure of said motor-circuit.

15. In combination, an electric motor, an air-compressor driven thereby, a pressure system supplied by said air-compressor, switching means governed by the pressure in said system to control the circuit for said motor, an automatic rheostat in the motor-circuit, means for preventing the operation of the valves of said pump during the initial supply of current to said motor, and electrical means for permitting the operation of said valves upon the lapse of a suitable interval after the closure of said motor-circuit.

16. In combination, an electric motor, a fluid-pump driven thereby, switching means for controlling the circuit through said motor, a resistance normally included in the motor-circuit, automatic means for gradually cutting said resistance out of the motor-circuit upon the closure of said circuit, electromagnetic mechanism normally included in the motor-circuit adapted upon the closure of the motor-circuit to prevent the operation of the valves of said compressor, and a slow-acting electromagnetic mechanism adapted to permit the operation of said valves after the lapse of a suitable interval after the closure of said motor-circuit.

17. In combination, a fluid-pump, a pressure system supplied thereby, motor means adapted to drive said pump, means governed by the pressure in said system for controlling the supply of energy to said motor means, and means for automatically raising the suction-valves of said pump off their seats during the initial supply of energy to said motor means.

18. In combination, a fluid-pump, a pressure system supplied thereby, motor means adapted to drive said pump, means for controlling the supply of energy to said motor

means, and electrical means for automatically preventing the operation of the suction-valves of said pump during the initial supply of energy to said motor means.

19. In combination, an electric motor, a fluid-pump driven thereby, switching means for controlling the motor-circuit, and automatic electrical means for preventing the operation of a valve of said pump during a limited period after the closure of the motor-circuit.

20. In combination, an air-compressor, an electric motor for driving said compressor, and automatic electrical means for preventing the operation of the suction-valves of said compressor during the initial supply of energy to said electric motor.

21. In combination, a fluid-pump, motor means for driving said pump, automatic electrical means for preventing the operation of the suction-valves of said pump upon the initial supply of energy to said motor means, and automatic means for allowing the operation of said suction-valves after the lapse of a suitable interval after the initial supply of energy to said motor means.

22. In combination, a fluid-pump having discharge-valves, an electric motor to drive said pump to normally cause compression of the fluid therein, whereby said discharge-valves are actuated, and electrical mechanism adapted upon closure of the motor-circuit to prevent compression of the fluid, whereby said valves are rendered inoperative.

23. In combination, a fluid-pump having discharge-valves, motor means for driving said pump for normally causing compression of the fluid therein and actuation of said discharge-valves, and electrical mechanism adapted during the initial supply of energy to said motor to automatically prevent compression of the fluid whereby said valves are rendered inoperative.

24. In combination, a fluid-pump, an electric motor for driving said pump, a pressure system supplied by said pump, switching means controlled by the pressure in said system to close the motor-circuit upon a decrease in the pressure in said system to a minimum limit and to open the motor-circuit upon an increase in the pressure in said system to a maximum limit, and automatic electromagnetic means adapted to prevent the operation of the suction-valves of said pump upon the closure of the motor-circuit.

25. In combination, a fluid-pump having discharge-valves, an electric motor for driving said pump to normally compress the fluid therein to cause actuation of said valves, a pressure system supplied by said pump, switching means controlled by the pressure in said system to close the motor-circuit upon a decrease in the pressure in said system to a minimum limit, and automatic electromagnetic

netic mechanism adapted upon the closure of the motor-circuit to prevent compression of fluid to render the valves inoperative.

26. In combination, an air-compressor having discharge-valves, an electric motor for driving said air-compressor to normally cause compression of air therein and actuation of the discharge-valves, a pneumatic pressure system supplied by said compressor, switching mechanism governed by the pressure in said system to cause the closure of the circuit through said motor upon a decrease in the pressure in said system to a minimum limit and to cause a break in the motor-circuit upon an increase in the pressure in said system to a maximum limit, a slow-acting automatic rheostat in the motor-circuit adapted to gradually short-circuit the resistances normally included in the motor-circuit after the closure of the motor-circuit, electromagnetic mechanism normally included in the motor-circuit adapted upon energization due to the closure of said motor-circuit to prevent compression of fluid and actuation of said valves, and a slow-acting electromagnetic switching device adapted to be actuated upon the short-circuiting of the last of said resistances to short-circuit the solenoids of said electromagnetic mechanism to allow compression of said fluid.

27. In combination, an electric motor, an air-compressor driven thereby, switching mechanism adapted to control the circuit for said motor, a slow-acting automatic rheostat in the motor-circuit adapted gradually to short-circuit resistances normally included in the motor-circuit after the closure of the motor-circuit, electromagnetic mechanism normally included in the motor-circuit adapted upon energization to prevent the operation of the suction-valves of said pump, and a slow-acting electromagnetic switching device adapted to be actuated after the lapse of a suitable interval of time to short-circuit the solenoids of said electromagnetic mechanism to permit the actuation of said valves.

28. In combination, a fluid-pump having discharge-valves, an electric motor for driving said pump, a pressure system supplied by said pump, means governed by the pressure in said system to control the motor-circuit, actuation of said motor normally causing compression of fluid in said pump and actuation of said discharge-valves, electromagnetic mechanism normally included in the motor-circuit adapted upon energization to prevent compression of fluid and actuation of said valves, and a slow-acting electromagnetic device included in the motor-circuit adapted to cause the deenergization of said electromagnetic mechanism after the lapse of a suitable interval of time after the closure of the motor-circuit.

29. In combination, a fluid-pump having discharge-valves, an electric motor for same,

a pressure system supplied by said pump, means governed by the pressure in said system to control the motor-circuit, operation of said pump normally causing compression of fluid therein and actuation of the discharge-valves, electromagnetic mechanism included in the motor-circuit adapted upon energization to prevent compression of fluid and actuation of said valves, and a slow-acting electromagnetic device included in the motor-circuit adapted to cause the deenergization of said electromagnetic mechanism after the termination of a limited period following the closure of the motor-circuit.

30. In combination, a fluid-pump having discharge-valves, an electric motor for driving said pump, the fluid in said pump being normally compressed and said valves actuated, electromagnetic mechanism normally included in the motor-circuit, adapted upon energization to prevent compression of fluid and actuation of said valves, and a slow-acting electromagnetic device included in the motor-circuit, adapted to cause the deenergization of said electromagnetic mechanism after the lapse of a suitable interval of time after the closure of the motor-circuit.

31. In combination, a fluid-pump having discharge-valves, an electric motor for driving said pump for normally causing compression of fluid therein and the actuation of said discharge-valves, electromagnetic mechanism included in the motor-circuit adapted upon energization to prevent compression of fluid and actuation of the valves, and a slow-acting electromagnetic device included in the motor-circuit adapted to cause the deenergization of said electromagnetic mechanism after the lapse of a suitable interval of time after the closure of the motor-circuit.

32. In combination, an electric motor, a fluid-pump driven thereby, a pressure system supplied by said pump, means governed by the pressure in said system to control the motor-circuit, electromagnetic means included in the motor-circuit adapted upon energization to prevent the operation of the suction-valves of said pump, and electromagnetic means adapted to permit the operation of said valves after the lapse of a suitable interval after the closure of the motor-circuit.

33. In combination, an electric motor, a fluid-pump driven thereby, a pressure system supplied by said pump, switching means controlled by the pressure in said system to control the circuit for said motor, electromagnetic mechanism included in the motor-circuit adapted upon energization to actuate the suction-valves of said pump to prevent the operation thereof, and slow-acting electromagnetic switching devices adapted to short-circuit and thereby cause the deenergization of said electromagnetic mechanism to permit the operation of said valves.

34. In combination, an electric motor, a

fluid-pump driven thereby, switching means for controlling the circuit through said motor, actuation of said pump normally causing compression of fluid therein and actuation of the valves thereof, and electrical mechanism adapted upon the closure of the motor-circuit to prevent compression of fluid and the actuation of said valves.

35. In combination with an electric motor, a fluid-pump driven thereby, switching means for controlling the circuit through said motor, the fluid in said pump being normally compressed to cause actuation of the valves of the pump, and automatic electrical mechanism adapted during the initial supply of current to said motor to prevent compression of fluid and actuation of the valves.

36. In combination, a fluid-pump, motor means for driving said pump, means for controlling the supply of energy to said motor means, the fluid in said pump being normally compressed therein to cause actuation of the valves of the pump, and automatic electrical mechanism adapted during a suitable period following the initiation of the supply of energy to said motor means for preventing compression of fluid and the actuation of said valves.

37. In combination, an electric motor, a fluid-pump driven thereby, a pressure system supplied by said pump, switching means controlled by the pressure in said system to govern the circuit for said motor, and means associated with the suction-valves of said pump and included in the motor-circuit for preventing the operation of said valves upon the closure of the circuit through said motor.

38. In combination, a fluid-pump, an electric motor driving said pump, a pressure system supplied by said pump, a controlling-valve for said pump, an electric circuit for said motor controlled by the pressure in said system, a resistance associated with the motor-circuit for restricting the current-flow to said motor, electromagnetic means controlled by the pressure in said system for removing said resistance from circuit, and means con-

trolled by the pressure in said system for preventing operation of said controlling-valves before said resistance is cut from circuit. 50

39. In combination, an electric motor, a fluid-pump driven thereby, a pressure system supplied by said pump, means directly subjected to the pressure in said system for controlling the circuit for said motor, electromagnetic means for preventing the operation of the valves of said pump during the initial supply of current to said motor, and additional electromagnetic means for incapacitating said other electromagnetic means 60 when said motor has reached normal speed whereby said valves become operative. 55

40. In combination, an electric motor, a fluid-pump driven thereby, a pressure system supplied by said pump, switching means 65 positively controlled by the pressure in said system to govern the circuit for said motor, and electromagnetic means for preventing the operation of the suction-valves of said pump upon closure of the circuit through 70 said motor.

41. An unloader for an air-compressor and electrically-controlled means arranged to complete a circuit for operating the unloader to cause it to unload the compressor before 75 the compressor is started.

42. An unloader for an air-compressor and electrically-controlled means for operating the unloader to cause it to unload the compressor before the compressor is started and 80 to throw the load onto the compressor at a predetermined point after the compressor is started.

43. An unloader for an air-compressor and electrically-operated means for controlling 85 the unloader comprising a rheostat and an electromagnet forming part of the rheostat resistance.

In witness whereof I hereunto subscribe my name this 27th day of June, A. D. 1903. 90
